UNITED STATES PATENT OFFICE.

HENRY J. FOSTER, OF CLEVELAND, OHIO, ASSIGNOR TO THE HYDRAULIC PRESSED STEEL COMPANY, OF CLEVELAND, OHIO, A CORPORATION OF OHIO.

SHEET-METAL FELLY.

1,379,810.

Specification of Letters Patent. Patented May 31, 1921.

Application filed May 13, 1918. Serial No. 234,106.

To all whom it may concern:

Be it known that I, HENRY J. FOSTER, a citizen of the United States, residing at Cleveland, in the county of Cuyahoga and State of Ohio, have invented a certain new and useful Improvement in Sheet-Metal Fellyes, of which the following is a full, clear, and exact description, reference being had to the accompanying drawings.

10 This invention relates generally to metal wheels and more particularly to a box felly to be used in connection with sheet metal wheels of either the disk or spoke type of construction.

15 The object of the invention is to provide a strong and durable felly which is adapted for use in connection with any and all types of felly bands to which are applied demountable tire carrying rims.

20 Another object of the invention is to provide a box felly of strong and durable construction and to which the felly band can be secured either by riveting or spot welding.

With these objects in view, and certain 25 others which will become apparent as the description proceeds, the invention consists in the novel features of construction and in the novel manner of combining the several features, all of which will be fully described hereinafter and set forth in the 30 claims.

In the drawings forming a part of this specification I have shown one embodiment of my invention and in which Figure 1 is a sectional perspective view showing a portion of the box felly; Fig. 2 is a plan view of a portion of the box felly; Fig. 3 is a plan view of a portion of the felly band; Fig. 4 is a plan view of a portion of the felly band 40 upon the box felly; Fig. 5 is a sectional view on the line 5—5 of Fig. 4; and Fig. 6 is a sectional view on the line 6—6 of Fig. 4.

The felly is made circular in form from a strip of sheet metal the ends of which are 45 united by welding. The felly comprises an inner or bottom portion A, side walls B, and the outer or top portion C. These outer or top portions C are the opposite edges of the metal strip turned inwardly and made to 50 approach each other as shown, said outer or top portions being parallel with the inner or bottom portions of the felly thereby providing with the side walls an angular box like structure.

55 Upon this box felly is arranged a felly

band D, carrying an inclined flange or shoulder E at the inner or rear edge thereof while at the outer or front edge there is provided a flange F projecting radially inward or toward the center of the wheel body. This 60 flange F snugly fits over the outer side wall of the box felly as most clearly shown in Figs. 5 and 6 and the edge G of this felly band is beveled as shown for the engagement of a wedge fastening ring or wedge clamp (not 65 shown) used in connection with the ordinary construction of automobile tire carrying rims for the purpose of securing said rims upon the wheel. The depending flange F may be omitted if desired. It will be 70 noted by reference to Fig. 2 that the top portions C are cut away at opposite points as shown at H so that when the felly is folded, central openings will be provided entirely around the box felly.

75 It will also be noted by reference to Fig. 3 that the felly band has a series of openings K produced therein, the relative location or spacing of these openings corresponding with the openings I in the box 80 felly and when the felly band is applied to the box felly, these openings K are brought directly in alignment with the openings I and by reference to Fig. 4 it will be seen that the openings K while of the same general contour as the openings I are slightly smaller so that the edges of the openings I are entirely concealed from view after the felly band has been properly placed. The openings I and K materially decrease the 85 weight of the device as a whole without materially detracting from the strength of the article as these openings are so positioned that the felly band and the box felly will not be weakened. In addition to making the 90 article lighter, provision is made for the insertion of suitable riveting or welding tools it being understood that the opposing members of said tools can be brought into 95 engagement with the top portion C and unremoved portion of the felly band, one member of these tools being inserted into the box felly through the openings I and K. Either method of connection may be employed and the points of riveting or welding 100 can be determined according to the necessities of the structure. When once rigidly connected however a complete unitary article will be provided having the maximum of 105 strength toward a given quantity of weight 110

and the felly structure will be provided capable of use in connection with any and all types of demountable tire carrying rims as it will be understood that the surface of the 5 felly band will be of the proper contour to receive its particular type of rim. It is also obvious that a felly structure of the kind described can be used in connection with either disk wheel bodies or spoked wheel 10 bodies and in fact could be used in connection with the ordinary wooden spokes.

Having thus described my invention, what I claim is:-

1. A felly comprising a bottom, side

walls, and inwardly projecting top portions 15 cut away at intervals, and a band having openings at intervals, and arranged upon and attached to said top portions, the openings in the band registering with the openings in the felly top.

2. A felly for metal spoked wheels adapted to receive a tire carrying rim comprising top, bottom and side portions, and a band arranged upon said top portion and having 20 25 openings at predetermined points.

In testimony whereof, I hereunto affix my signature.

HENRY J. FOSTER
